GOLF BALL TEEING DEVICE

J. Royal Parker, Malverne, and Joseph A. Idank, Richmond Hill, N. Y., assignors to The Lazy Golfer Corporation

Application December 28, 1953, Serial No. 28,229

Term of patent 3½ years

(Cl. D34—5)

FIG. 1.

FIG. 2.

FIG. 3.

To all whom it may concern:

Be it known that we, J. Royal Parker and Joseph A. Idank, have invented a new, original, and ornamental Design for a Golf Ball Teeing Device, of which the following is a specification, reference being had to the accompanying drawings, forming a part hereof.

Figure 1 is a top plan view of a golf ball teeing device, showing our new design,

Figure 2 is a side elevational view thereof, and

Figure 3 is a rear elevational view thereof.

We claim:

The ornamental design for a golf ball teeing device, substantially as shown.
